UNITED STATES PATENT OFFICE.

GEORGE W. HARRIS, OF ELIZABETH, NEW JERSEY, AND HORATIO P. ALLEN, OF NEW YORK, N. Y.

IMPROVEMENT IN THE MANUFACTURE OF ILLUMINATING-GAS.

Specification forming part of Letters Patent No. 129,951, dated July 30, 1872.

Specification describing certain Improvements in the Form, Arrangement, and Setting of Retorts, to be used for the production of permanent gases from steam, by the action of incandescent carbon, iron, or other suitable agent, invented by GEORGE W. HARRIS, of the city of Elizabeth, county of Union, State of New Jersey, and HORATIO P. ALLEN, of the city, county, and State of New York.

Our invention consists, first, in the use of retorts of any form of transverse section, circular, elliptical, or otherwise, set vertically; second, in an arrangement of such retorts around a furnace or fire-space, concentrically, in a bench inclosed in an outer cylindrical wall, the flues and passages for the flame from the fire-space being arranged suitably for conveying a uniform temperature to each retort and to all parts thereof; third, in a construction of the top mouth-pieces of the retorts, through which their contents are introduced by the attachment of lateral horizontal delivery-pipes, for the conveyance of the gaseous products to a common central vertical main pipe; fourth, in a construction of the bottom mouth-pieces, through which the ashes and residuum are removed from the retorts, in such manner as to operate as distributors of the steam, the upper part of each mouth-piece being provided with an annular space or chamber, from which the steam passes through numerous small perforations, in jets, directly into the incandescent material contained in the retorts; fifth, in the construction of passages within the thickness of the outer wall adjoining the fire-brick lining of the fire-space, through which the steam-pipes pass on their way to the distributors, which arrangement results in the superheating of the steam to a high degree without exposure of the steam-pipes to the direct action of the flame.

Figure 1 is a horizontal section of our improved bench, in which the relative positions of the retorts A A, the furnace B, the flues M M M, and the superheating-passages H H in the inclosing-wall W W W are represented. Fig. 2 is a vertical section of the same, showing the positions of the retorts A A, the furnace B, the top mouth-pieces D D, and the bottom mouth-pieces E E, with their attachments

G G for discharging the residuum and distributing the steam. F F are the pipes through which the steam is brought into the annular chambers G G, which operate as distributors. H H are the passages constructed in the thickness of the wall adjoining the fire-brick K K, through which the pipes F F have been conducted in order to superheat the steam. The pipes F F may be composed of wrought or cast-iron, fire-clay, or other suitable material. L L is the large main flue to receive the small circularly-arranged flues M M M, shown in Fig. 1.

The dimensions which we prefer for these retorts are seven feet in height by two feet in internal diameter; but these may vary, of course, to some extent.

In operation, the retorts are filled with any material which will combine with the oxygen of the steam and eliminate its hydrogen. We use generally anthracite coal, though coke and charcoal are available. To obtain pure hydrogen metallic iron may be used. These materials are introduced through the top mouth-piece or cover.

The principal advantages derived from this improvement over ordinary horizontal gas-retorts, when used for the same purposes, are, greater facility of charging at the top, and of discharging the ashes and residuum at the bottom without removing, necessarily, the whole contents; the very much greater depth of incandescent material through which the steam must pass; the saving of labor and fuel by heating a larger number of retorts in one bench or by one fire, and so on.

Claims.

We claim as our invention—

1. The use of several vertical retorts, arranged radially around one furnace, for the decomposition of steam into permanent gases, substantially as described.
2. The arrangement of lateral delivery-pipes, converging to a central vertical main pipe, from a circle of vertical retorts in which steam is decomposed, substantially as described.
3. The combination, with the bottom mouth-piece of a vertical retort used for decomposing steam into permanent gases, of an annular

chamber, perforated with holes, for the delivery of steam in jets into such retorts, substantially as described.

4. The arrangement, for superheating steam to be decomposed into permanent gases, of passages constructed in the wall of the oven which heats the retorts on the outside of the

fire-brick lining, through which the steam-pipes pass, substantially as described.

GEO. W. HARRIS.
H. P. ALLEN.
